UNITED STATES PATENT OFFICE.

GOTTLOB AICHELE, OF NELLINGEN, NEAR ESSLINGEN, GERMANY, ASSIGNOR, BY MESNE ASSIGNMENTS, TO DAIMLER-BENZ AKTIENGESELLSCHAFT, OF BERLIN, GERMANY.

TYPEWRITING MACHINE.

Application filed October 19, 1926, Serial No. 142,735, and in Germany March 27, 1924.

This invention comprises improvements in and connected with reversible ribbon feed-
ing mechanisms for typewriting and like
machines and is concerned with mechanisms

5 of the type in which the reversal of the rib-
bon feed is initiated by a pin arranged in the
hollow vertical spindle of a bobbin and which
is permitted to fall or move axially upon the
unwinding of the ribbon from that bobbin.

10 The object of the invention is to attain
greater reliability in the operation of the
parts, simplification in the manufacture, and
increased strength and resistance to distortion
with avoidance of employment of such
15 elements as are liable to derangement.

According to this invention, a lever oscillated by the bobbin drive communicates oscillatory movement through a rod arrangement to a second lever which operates upon
20 tongs-like feed levers, the axially movable
pin in the bobbin being adapted, when re-
leased, to so modify the oscillation of the
second lever as to bring about an operative
engagement of the feed levers of the empty
25 bobbin and a disengagement of the feed
levers of the full bobbin, the said feed levers
being engaged or disengaged by closing
movement towards one another or by open-
ing movement away from one another, as
30 the case may be.

The driving lever and the second or re-
versing lever of each bobbin are preferably
arranged to oscillate about a common pivot
and the rod connection between the revers-
35 ing levers is advantageously mounted slide-
ably within a bore of the rod which trans-
mits the motion from one driving lever to
the other.

40 The mechanism in accordance with this in-
vention is distinguished by the employment
of a comparatively small number of very
simple parts, with avoidance, as far as pos-
sible, of cranks. The mechanism also is dis-
tinguished by parts moving in the same plane
45 or in parallel planes, as far as possible,
whereby bending or distortion of the small
parts functioning in the transmission is pre-
vented.

50 In order to enable the invention to be
readily understood, reference is made to the
accompanying drawing illustrating one em-
bodiment of the invention by way of ex-
ample, in which drawing:—

Figure 1 is a view from below of a re-

versible ribbon feed mechanism embodying 55
the invention showing the parts in the po-
sition for winding on by the left hand spool
and unwinding by the right hand spool.

Figure 2 is a view of the mechanism after
reversal from the position seen in Figure 1. 60

Figure 3 is a sectional side elevation of
Figure 1.

Figure 4 is a vertical section through one
of the spools and its associate parts.

Referring to the drawings, 1 is a cover 65
plate with housings 2, 3, for the spools, the
spool pivots or spindles 4 being mounted
centrally within the housings. The spools
5 are mounted on their spindles 4 in known
manner being secured by knurled nuts 6, for 70
example. The left hand bobbin 5 is adapted
for being driven by a spring through a mech-
anism which acts upon the bevel wheel 7.
The last named is mounted upon the spindle
part 8 of the cam 9 which is arranged in a 75
bearing bracket 10. A pin or roller 11 on
the lever 12 engages with the cam 9 for os-
cillating the lever 12 about the pivot 13,
the end of the lever 12 being shaped for re-
ceiving guidance in the guide 14 of the bear-
ing bracket 10. An arm 15 of the lever 12
engages in an aperture in an extension at
one end of a hollow rod 16, as will be readi-
ly understood by comparing Figures 1 and 3,
an extension at the opposite end of the rod 85
16 being similarly engaged with an arm of
a lever 17 corresponding with the lever 12,
15. The lever 17 oscillates about a pivot 18
mounted in the bobbin housing 3. The end
19 of the lever 17 is guided in a recess 20 90
corresponding with the guide 14 of the lever
12. Toothed rack levers 21 and 22 are piv-
otally mounted on the lever 12 at the points
23, 24, and their free ends are connected
together by a spring 25 which constantly 95
tends to bring the levers together and hold
them against opposite points of the toothed
wheel 26 on the left hand spool spindle 4.
Toothed rack levers 27 and 28 are pivotally
mounted at 29, 30 on the lever 17, the free
ends of these levers being connected together
by a spring 31 constantly tending to hold
them in mesh with opposite points of the
toothed wheel 32 on the spindle of the right
hand spool.

In Figure 1 it is assumed that the spool
in the housing 2 is winding on and that the
spool in the housing 3 is unwinding. In

operation, the cam 9 is driven by the bevel wheel 7 and the lever 12 is oscillated owing to the engagement with the cam 9 of the pin or roller 11. The rack levers 21 and 22 mesh with the toothed wheel 26 owing to the action of the spring 25, the wheel 26 being of the ratchet type and the teeth of the levers 21 and 22 being directed so that on one swing the teeth of the lever 22 slip, the reverse being the case on the opposite swing. Continuous motion is thus imparted to the spool spindle and spool, the motion being uniform owing to the heart-shape of the cam 9. Meanwhile, the rack levers 27, 28 of the other spool are out of engagement with the wheel 32 as seen in Figure 1, being spread apart by a mechanism hereinafter described, but they move to and fro with the lever 12 and rack levers 21 and 22 owing to the rod 16 connecting together the levers 12 and 17. This operation continues and the left hand spool continues to wind on and the right hand spool continues to unwind under the pull of the ribbon until the latter spool is empty when the reversal takes place as hereinafter described.

A small pin or rod 33 is inserted in the bore of the hollow spindle of each spool, as seen best in Figure 4, and in each spool at 34 there is pivoted a small lever having arms 35 and 36. The arm 36 is adapted to project through a slot in the spool when the ribbon is completely unwound therefrom. When the spool is empty, the arm 36 is free to move out into the projecting position seen in Figure 4 under the influence of the pin or rod 33 which drops under its own weight, a projection on the lower end of the pin or rod 33 then entering a slot 37 formed in an enlarged part 38 on the end of a reversing lever 39. One lever 39 is mounted on the pivot 13 in association with the lever 12 and another lever 39 is mounted on the pivot 18 in association with the lever 17. The upper ends 40 of the levers 39 are engaged by pin and fork engagement with the extended ends of a rod 41 slidably mounted within the bore of the hollow rod 16. The enlargements 38 of the levers 39 are fitted with pins 43 adapted for engaging suitably inclined and formed edges on end enlargements of the rack levers 21, 22 and 27, 28. In Figure 1, the pin 43 of the left hand lever 39 is out of engagement with the consequence that the rack levers 21, 22 are free to be pulled together by the spring 25 so that they are held in mesh with the ratchet 26. The pin 43 of the right hand lever 39, however, is seen to be in engagement with the appropriate parts of the rack levers 27, 28, so that these levers are spread and their rack teeth fail to mesh with the ratchet wheel 32. Whilst either of the spools retains any coils of ribbon, the lever arms 36 are prevented from projecting by such coils

so that the pins 33 cannot drop and cause any hindrance to the free swinging and working of the parts. As soon as the right hand spool becomes empty its lever arm 36 is free to move out through the slot as above described and the pin 33 drops so that its projection 42 enters the slot 37 of the right hand lever 39. This effects an arrest of the right hand lever 39 in its swinging motion which has up till this moment been in consonance with the swing of the levers 12 and 17, each of the levers 39 having been in fixed angular relation to the appropriate lever 12 or 17, owing to the fact that there has been nothing to disturb this relative positioning of the levers. As soon as the right hand lever 39 is arrested, however, the relation is upset for the levers 12 and 17 continue to swing under the action of the driving means above described. Thus, the rod 16 will be moved over the rod 41, the enlargements of the rack levers 21 and 22 will be forcibly brought against the pin 43 of the left hand lever 39 whilst the enlargements of the rack levers 27 and 28 will be moved away from the pin 43 of the right hand lever 39. The result will be that the levers 21 and 22 will be spread to the position seen in Figure 2 so that their racks no longer mesh with the ratchet wheel 26, whereas the levers 27 and 28 will be drawn towards one another by their spring so that they will mesh with the ratchet wheel 32. The right hand spool will now wind on ribbon whilst ribbon will be freely unwound from the left hand spool. Immediately the lever arm 36 of the right hand spool is lapped by the ribbon it will be forced back through its slot and will lift its pin 33 and release the latter from the slot 37 of the right hand lever 39, the parts being now free to swing and feed ribbon on to the right hand spool until the latter is full and the left hand spool is empty, as will be readily understood.

The direction of winding and the reversal are indicated by a pin 44 on the rod 41 projecting through a slot 45 in the rod 16. As will be seen by comparing Figures 1 and 2, the pin 44 lies to the left hand end of the slot 45 when the left hand spool is winding on and to the right hand end of the slot 45 when the right hand spool is winding on.

Having thus described my invention what I claim is:

1. Reversible ribbon feeding mechanism for typewriting and like machines, comprising a ribbon spool, a pin axially slidably in said spool, means permitting the pin to drop when the ribbon is unwound from the spool, a reciprocating rod, drive gearing for said spool including a drive lever driven by said reciprocating rod and a pair of tong-like feed levers pivoted to said drive lever, and means controlled by the dropping of said pin for throwing said drive gearing into gear, 125

said means including an oscillating reversing lever having a slot adapted to receive said pin whereby the oscillation of said reversing lever is limited, and a second reciprocating rod adapted to actuate said reversing lever.

5 2. Mechanism as specified in claim 1, wherein the drive lever and the oscillating lever are mounted on a common pivot.

10 3. Mechanism as specified in claim 1, wherein the second reciprocating rod is slid-

ably mounted within the first mentioned reciprocating rod.

4. Mechanism as specified in claim 1, wherein the drive lever and the oscillating 15 lever are mounted on a common pivot, and the second reciprocating rod is slidably mounted within the first mentioned reciprocating rod.

In testimony whereof I affix my signature.

GOTTLOB AICHELE.
